(57) **ABSTRACT**

Disclosed is a multi-cone small loudspeaker, including a cone assembly. The cone assembly includes a central cone and a plurality of outer cones, and the plurality of outer cones are successively arranged in a circumferential direction of the central cone. The central cone is driven by a central driving mechanism to vibrate and sound, each of the plurality of outer cones is respectively driven by one outer driving mechanism to vibrate and sound. The central driving mechanism includes a central voice coil connected to the central cone, and a central magnetic driving system for driving the central voice coil. Each outer driving mechanism includes an outer voice coil connected to one of the plurality of corresponding outer cones, and an outer magnetic driving system for driving the outer voice coil.

MULTI-CONE SMALL SPEAKER

This application is the U.S. National Phase under 35 U.S.C. § 371 of International Application PCT/CN2021/122621, filed Oct. 8, 2021, which claims the priority to Chinese Patent Application No. CN202010908027.6, filed Sep. 2, 2020. The disclosures of the above-described applications are hereby incorporated by reference in their entirety.

FIELD OF TECHNOLOGY

The present disclosure belongs to the field of loudspeaker, and relates to a multi-cone small loudspeaker, and in particular to a multi-cone small loudspeaker with no damper and can be input multiple audio input signals.

BACKGROUND

The cone adopted by the existing traditional small loudspeakers with no damper is generally disc-shaped, and is connected to a voice coil to form a loudspeaker vibration system without a damper. This type of loudspeaker with no damper can only be applied to single-channel signal input, however, single-channel audio signal input has limitations for sound reproduction, and when a single voice coil is combined with a cone, there is a high requirement for the rigidity of the cone material. Although the voice coil of this type of loudspeaker can also adopt a multi-channel signal inputting voice coil, such voice coil is formed by multiple sets of coils stacked from inside to outside, the disc-shaped cone and the damper are respectively glued to an outer wall of the voice coil to form a vibration system of the loudspeaker, and this type of loudspeaker can be applied to multiple signal inputs. However, due to the fact that such loudspeaker has one voice wounded by multiple groups of coils, and the multiple groups of coils wound into one voice coil increases the weight of the voice coil, the sensitivity of the loudspeaker may be affected and may decrease when the voice coil drives the cone. Although it is reported that multiple magnetic driving systems are used to drive multiple voice coils respectively, the sound reproduction clarity of the loudspeaker needs to be improved.

SUMMARY

The present disclosure relates to a multi-cone small loudspeaker with no damper, which improves the sound reproduction clarity and has high sensitivity.

A multi-cone small loudspeaker includes a frame and a cone assembly arranged on the frame, the cone assembly comprises a central cone and a plurality of outer cones, the plurality of outer cones is successively arranged in a circumferential direction of the central cone, the small loudspeaker further comprises a central driving mechanism and a plurality of outer driving mechanisms arranged around a periphery of the central driving mechanism, the central cone is driven by the central driving mechanism to vibrate and sound, each of the outer cones is respectively driven by one outer driving mechanism to vibrate and sound, the central driving mechanism comprises a central voice coil connected to the central cone, and a central magnetic driving system for driving the central voice coil, and each outer driving mechanism respectively comprises an outer voice coil connected to the outer cone, and an outer magnetic driving system for driving the outer voice coil.

In some embodiments, the plurality of outer cones is interconnected to form a ring surrounding the central cone,

2

and the central cone and the plurality of outer cones are independently arranged on the frame. More preferably, the shape of each outer cone is generally an annular sector. Further, the area of each outer cone is generally equal.

5 In some embodiments, the frame comprises a frame bottom and an inner flange extending upwards from the frame bottom, and an outer edge of the central cone is fixedly connected to the inner flange.

In some embodiments, the frame further comprises an 10 outer part and a plurality of middle flanges respectively extending upwards from the frame bottom, the outer part surrounds an outer periphery of the inner flange, the middle flanges are located between the inner flange and the outer part, an outer edge of each of the outer cone is fixedly 15 connected to the outer part, an inner edge of each of the outer cones is fixedly connected to the inner flange, and two side edges of each of the outer cones are fixedly connected to two adjacent middle flanges.

In some embodiments, the middle flanges radially extend 20 along the frame bottom, and each of the outer cones is substantially in a shape of annular sector.

In some embodiments, the frame comprises a frame bottom and an inner flange extending upwards from the frame bottom, and an outer part and middle flanges, the outer 25 part surrounds an outer periphery of the inner flange, the middle flanges radially extend along the frame bottom and are located between the inner flange and the outer part, the outer edge of the central cone is fixedly connected to the inner flange, each of the outer cones is substantially in a 30 shape of annular sector, an outer edge of each of the outer cones is fixedly connected to the outer part, an inner edge of each of the outer cones is fixedly connected to the inner flange, and two side edges of each of the outer cones are fixedly connected to two adjacent middle flanges.

In some embodiments, the central magnetic driving system and the outer magnetic driving systems are fixedly arranged on the frame bottom, and the central voice coil and the outer voice coils are located between the cone assembly and the frame bottom.

35 In some embodiments, the central magnetic driving system and the outer magnetic driving systems are fixedly arranged below the frame bottom, the frame bottom is opened with a central through-hole and a plurality of peripheral through-holes, a lower end of the central voice coil is 40 inserted into a magnetic gap of the central magnetic driving system through the central through hole, and a lower end of each of the respective outer voice coils is inserted into a magnetic gap of one of the outer magnetic driving systems through one of the peripheral through-holes.

45 Further, the frame bottom is substantially in a shape of annular sector.

Further, each of the central magnetic driving system and the outer magnetic driving systems comprises a U-yoke having a cavity, and a magnet and a magnetic pole core 50 arranged within the U-yoke, an upper end of the U-yoke is fixedly connected to the frame bottom, and a magnetic gap into which the central voice coil or one of the outer voice coils is inserted is formed between the magnet and the magnetic pole core and an inner wall of the U-yoke.

55 In some embodiments, each of the central voice coil and the outer voice coils has a pair of leads, an end portion of each of the leads is connected with a inputting terminal that can be electrically connected to a power amplifier, and the inputting terminal(s) is embedded on a lower surface of the frame bottom. Further, an outer surface of the outer part is 60 provided with a plurality of outlet slots respectively corresponding to the inputting terminals.

In some embodiments, the inner flange and the outer part are respectively ring-shaped and concentric.

In some embodiments, the frame bottom is a circular plate as a whole, and the center of the circle is the center of the frame bottom.

In some embodiments, the central portion of the central cone has an upward arched spherical dome or a flat plate-shaped main body, and the outer cones has flat plate-shaped main bodies. When the central cone and the outer cones adopt the flat plate-shaped main bodies respectively, the height of the central cone and the outer cones can be lower than the height of the traditional disc-shaped cone, and the product directivity width is better than that of the loudspeaker with a traditional disc-shaped cone.

In some embodiments, a fixing step is formed on a lower surface of the central cone to connect to the central voice coil; and/or, a plurality of fixing steps are formed on lower surfaces of the outer cones to connect to the outer voice coils.

In some embodiments, the plurality of outer driving mechanisms is arranged around the periphery of the central driving mechanism at equal intervals.

In some embodiments, the small loudspeaker does not comprise damper.

Here, "multi-cone" means that the total number of cones is equal to or more than three, preferably at least four.

The small loudspeaker of the present disclosure has an ingenious and reasonable product structure, the central cone is promoted to sound by inputting an audio signal to the central voice coil to vibrate up and down in the central magnetic driving system, and the plurality of outer cones is promoted to sound by inputting multi-channel audio signals respectively to the plurality of outer voice coils to vibrate up and down in the outer magnetic driving systems, the central cone emits a midrange and treble sound, and the outer cones increase and expand the bass performance of the loudspeaker, broadens the frequency bandwidth and directivity of the loudspeaker, and reduces the distortion of the loudspeaker; through the combination of the central voice coil and the plurality of outer voice coils, and through driving the respective cones by the central magnetic driving system and the outer magnetic driving systems, the sensitivity of the loudspeaker is increased; by inputting multi-channel audio signals into the central voice coil and the outer voice coils respectively, the central cone and the outer cones are promoted, which can improve the sound reproduction effect of the loudspeaker. In addition, the respective outer voice coils are independent of each other, and the audio signals input to the respective outer voice coils can be different, therefore, the small loudspeaker is suitable for use as a digital loudspeaker and can be used to construct a digital loudspeaker system.

BRIEF DESCRIPTION

For more clearly explaining the technical solutions in the embodiments of the present disclosure, the accompanying drawings used to describe the embodiments are simply introduced in the following. Apparently, the below described drawings merely show a part of the embodiments of the present disclosure, and those skilled in the art can obtain other drawings according to the accompanying drawings without creative work.

FIG. 1 is a schematic exploded view of a small loudspeaker according to an embodiment of the present disclosure.

FIG. 2 is a schematic diagram of the frame and the voice coil in FIG. 1.

FIG. 3 is a schematic front view of the frame with the voice coil mounted thereon in FIG. 1.

5 FIG. 4 is a schematic back view of the frame with the voice coil mounted thereon in FIG. 1.

Detailed Description of Exemplary Embodiments

In the following, the preferable embodiments of the present disclosure are explained in detail combining with the accompanying drawings so that the advantages and features of the present disclosure can be easily understood by the skilled persons in the art. It should be noted that the explanation on these implementations is to help understanding of the present disclosure, and is not intended to limit the present disclosure.

25 As shown in the specification and the claims, the terms "comprising" and "containing" only indicate that the clearly identified steps and elements are included, and these steps and elements do not constitute an exclusive list, and the method or device may also include other steps or elements. The term "and/or" as used herein includes any combination of one or more of the associated listed items.

30 In the description of the present application, it should be understood that the orientations or positional relationships indicated by the terms "center", "periphery", "upper", "lower", "left", "right", "vertical", "horizontal", "top", "bottom", "inner" and "outer", etc. are based on those shown in the accompanying drawings, are only for the convenience of describing the present application and simplifying the description, rather than indicating or implying that the indicated device(s) or element(s) must have a specific orientation, be constructed and operated in a specific orientation, and therefore should not be construed as a limitation of the present application.

35 In the description herein, it should be noted, unless otherwise expressly specified and limited, the terms "mount", "communicate" and "connect" and other terms should be understood in a broad sense, for example, it may be fixedly connected or detachably connected, or integrated;

40 it may be mechanically connected or electrically connected; it can be directly connected or indirectly connected through an intermediate medium, or it can be the internal communication of two elements. For those of ordinary skill in the art, the specific meanings of the above terms in the present disclosure can be understood according to specific situations. On the contrary, when an element is referred to as "directly on" another element, there is no intermediate medium.

45 This embodiment provides a multi-cone small loudspeaker, specifically a loudspeaker without a damper. Here, "multi-cone" means that the total number of cones is equal to or more than three, preferably at least four. Referring to

FIG. 1 to FIG. 4, the multi-cone small loudspeaker comprises a frame 1 and a cone assembly 2 arranged on the frame 1. The cone assembly 2 comprises a central cone 21 and a plurality of outer cones 22, the plurality of outer cones 22 is successively arranged in a circumferential direction of the central cone 21, and the central cone 21 and the plurality of outer cones 22 are independently arranged on the frame 1 and do not interfere with each other. The small loudspeaker further comprises a central driving mechanism for driving the central cone 21 to vibrate and sound and a plurality of outer driving mechanisms for driving the outer cones 22 to vibrate, the outer driving mechanisms are arranged around the periphery of the central driving mechanism, each outer driving mechanism corresponds to one outer cone 22, and the respective outer cones 22 are driven by the corresponding outer driving mechanisms to vibrate and sound. Further, the plurality of outer driving mechanisms is arranged around the periphery of the central driving mechanism at equal intervals. The central driving mechanism comprises a central voice coil 31 connected to the central cone 21, and a central magnetic driving system 4a for driving the central voice coil 31, and each outer driving mechanism respectively comprises an outer voice coil 32 connected to the corresponding outer cone 22, and an outer magnetic driving system 4b for driving the outer voice coil 32. Preferably, the number of the outer voice coils 32 is three or more, and are arranged in a circle at equal intervals, the center of the circle falls on the midpoint of the central voice coil 31. The central cone 21 is driven by the central voice coil 31 to vibrate and sound, and the central cone 21 undertakes medium and high-frequency sound production. The respective outer cones 22 are driven by the corresponding outer voice coils 32 to vibrate and sound, and the outer cones 22 undertake low and medium-frequency sound production. The plurality of outer voice coils 32 can input multiple different analog or digital audio signals, which improves the sound reproduction performance of the loudspeaker.

When viewing from the top, the central cone 21 has a substantially circular outer contour. The plurality of outer cones 22 is interconnected to form a ring surrounding the central cone 21. Preferably, as shown in FIG. 1, the shape of each outer cone 22 is generally a fan-shaped ring as a whole, and the area of each outer cone 22 is generally equal. In the embodiment as shown in FIG. 1, three outer cones 22 are successively arranged at the periphery of the central cone 21. The central cone 21 is arranged at the center of the frame 1, and the plurality of outer cones 22 is independently arranged on the frame 1. In one embodiment, the central cone 21 and the outer cones 22 respectively have flat plate-shaped main bodies, and reinforcing ribs are arranged on the back (specifically the side surface opposite to the frame 1) of the main bodies of the central cone 21 and the outer cones 22 to improve the working strength and rigidity, which is used to enhance the strength of the voice coil when it pushes the cone. The height of the central cone 21 and the outer cones 22 is lower than the height of the traditional disc-shaped cone, and at the same time, when the central cone 21 and the outer cones 22 adopt the flat-plate shape, the product directivity width is better than that of the loudspeaker with a traditional disc-shaped cone. In another embodiment, the central portion of the central cone 21 has an upward arched spherical dome 211, to increase treble frequency extension.

Combining FIG. 2 with FIG. 3, the frame 1 comprises a frame bottom 11 and an inner flange 12 extending upwards from the frame bottom 11, and an outer part 13 and middle flanges 14. The inner flange 12 has a ring as a whole, which roughly matches the outer contour of the central cone 21.

The outer part **13** surrounds the outer periphery of the inner flange **12**, and is also roughly ring-shaped, and the two are roughly concentric rings, i.e., share the same center. The frame bottom **11** is a round flat plate as a whole, the center is also the center of the frame bottom **11**. The middle flanges **14** radially extend along the frame bottom **11**, and are located between the inner flange **12** and the outer part **13**. The outer edge of the central cone **21** is fixedly connected to the inner flange **12**. The inner edges of the respective outer cones **22** are fixedly connected to the inner flange **12** through edge rings **221**, respectively, and the inner edges of the outer cones **22** and the outer edge of the central cone **21** do not overlap, and are not connected to each other. The outer edges of the respective outer cones **22** are connected to the outer part **13** through the edge rings **221**, respectively. Two side edges of each outer cone **22** are fixedly connected to two adjacent middle flanges **14** through the edge rings **221**, and sides of two adjacent outer cones **22** are not connected to each other, and separated by a ridge on the corresponding middle flange **14**. The central magnetic driving system **4a** and the outer magnetic driving systems **4b** are fixedly arranged on the frame bottom **11**, and the central voice coil **31** and the outer voice coils **32** are located between the cone assembly **2** and the frame bottom **11**. Preferably, the central magnetic driving system **4a** and the outer magnetic driving systems **4b** are fixedly arranged below the frame bottom **11**, the frame bottom **11** is opened with a central through-hole **111** and a plurality of peripheral through-holes **112**, the central through-hole **111** is opened in the inner flange **12**, and the peripheral through-holes **112** are opened between two adjacent middle flanges **14**. A lower end of the central voice coil **31** is inserted into a magnetic gap of the central magnetic driving system **4a** through the central through hole **111**, and lower ends of the respective outer voice coils **32** are inserted into magnetic gaps of the outer magnetic driving systems **4b** through the corresponding peripheral through-holes **112**.

Referring to FIG. 1, each of the central magnetic driving system 4a and the outer magnetic driving systems 4b comprises a U-yoke 41 having a cavity, and a magnet 42 and a magnetic pole core 43 arranged within the U-yoke 41, an upper end of the U-yoke 41 is fixedly connected to the frame bottom 11, and a magnetic gap into which the central voice coil 31 or the outer voice coils 32 are inserted is formed between the magnet 42 and the magnetic pole core 43 and an inner wall of the U-yoke 41. The above-mentioned central through-hole 111 is opened at the center of the frame bottom 11, an upper end of the U-yoke 41 of the central magnetic driving system 4a is fixedly arranged within the central through-hole 111, the neodymium magnet 42 and the magnetic pole core 43 are mounted within the U-yoke 41, the lower surface of the magnetic pole core 43 is tightly fitted with the upper surface of the magnet 42, the lower surface of the magnet 42 is tightly fitted with the upper surface of the bottom of the U-yoke 41, and there is a gap between the outer surfaces of the magnetic pole core 43 and the magnet 42 and the inner side surface of the U-yoke 41, thus forming a magnetic gap into which the central voice coil 31 is inserted. The above-mentioned plurality of peripheral through-holes 112 are distributed evenly around the central through-hole 111, upper ends of the U-yokes 41 of the respective outer magnetic driving systems 4b are fixedly arranged within the corresponding peripheral through-holes 112, the magnets 42 and the magnetic pole cores 43 are mounted within the U-yokes 41, the lower surfaces of the magnetic pole cores 43 are tightly fitted with the upper surfaces of the magnets 42, the lower surfaces of the

magnets 42 are tightly fitted with the upper surfaces of the bottoms of the U-yokes 41, and there are gaps between the outer surfaces of the magnetic pole cores 43 and the magnets 42 and the inner side surfaces of the U-yokes 41, thus forming magnetic gaps into which the outer voice coils 32 are inserted. Preferably, the frame 1 is formed by plastic injection molding, and the U-yokes 41 are embedded in the frame 1 during the injection molding process, which improves the combination accuracy.

As shown in FIG. 3 and FIG. 4, each of the central voice coil 31 and the respective outer voice coils 32 has a pair of leads 33. An end portion of each lead 33 is connected with one inputting terminal 34 that is embedded in the outer part 13. Specifically, each voice coil is provided with 1 group of positive and negative leads 33, and each group of leads 33 are connected to two inputting terminals 34 on the outer part 13. When connect the loudspeaker to a power amplifier, a male connector connected to the power amplifier can be inserted into a female connection port 131, to conduct the inputting terminals 34 therein, and to achieve the transmission of audio signals. The outer surface of the outer part 13 is provided with a plurality of outlet slots 131, and each inputting terminal 34 corresponds one outlet slot 131, to hold a wire for connecting the inputting terminal 34 with the outside. By inputting multiple analog audio signals or multiple digital audio signals to the central voice coil 31 and the respective outer voice coils 32 by the plurality of inputting terminals 34, the sound reproduction performance of the loudspeaker is improved.

A fixing step is formed on a lower surface of the central cone 21 to connect to the central voice coil 31, and the upper end of the central voice coil 31 is tightly fitted with the fixing step. Fixing steps are formed on lower surfaces of the respective outer cones 22 to connect to the outer voice coil 32s, and the upper ends of the outer voice coils 32 are tightly fitted with the fixing steps.

The material of the above-mentioned frame 1 is plastic or metal. The central cone 21 and the outer cones 22 are made of different materials, such as plastic (PP), paper, cloth (silks), metal or alloy (aluminum alloy), and can be a film-like material. The edge rings 221 are made of the same material as the outer cones 22, or sponge, rubber, cloth or combinations thereof. They have the advantages of light weight, good damping elasticity and rigidity, high and low temperature resistance, waterproof and mold-proof.

The small loudspeaker of this embodiment has the following characteristics: by providing the central cone 21 with the spherical dome 211 in the center of the frame 1, providing the step for fixing the voice coil at the lower end of the central cone 21, and fixing the central voice coil 31 on the fixing step of the central cone 21, a vibration system for the midrange and treble sound production is formed; three outer cones 22 with an overall flat shape are provided evenly at the periphery of the central cone 21, the inner side edges and outer side ends of the outer cones 22 are provided with the edge rings, the bottoms of the outer cones 22 are provided with the steps for fixing the voice coils to fix the three outer voice coils on the steps of the corresponding outer cones 22, and to form a vibration system for bass and midrange sound production, thus forming a multi-cone multi-magnetic circuit loudspeaker with no damper. Such a loudspeaker adopts a multi-cone, multi-magnetic circuit and multi-voice coil drive structure, and when compared with the traditional loudspeaker with no damper, a plurality of cones is used, that is, the central cone 21 undertakes the midrange and treble sound production, the plurality of outer cones 22 undertakes the bass and midrange sound produc-

tion, the combination of multiple cones is conducive to improving the sound reproduction clarity of the loudspeaker, and the bass and directional width of the loudspeaker is also better than that of the loudspeakers with traditional cones; by using a single-channel signal input to drive the central voice coil 31 to move up and down in the magnetic circuit of the U-yoke 41, and by using a multi-channel signal input to drive the plurality of voice coils to move up and down in the magnetic circuits of the plurality of U-yokes 41, the center cone 21 and the flat plate-shaped outer cones 22 are pushed to sound, the sensitivity of the loudspeaker may be increased, and the distortion of the loudspeaker may be reduced.

The small loudspeaker has an ingenious and reasonable product structure, and the central cone 21 (plane or spherical) is promoted to sound by inputting an audio signal to the central voice coil 31 to vibrate up and down in the central magnetic driving system; the plurality of outer cones 22 is promoted to sound by inputting multi-channel audio signals respectively to the plurality of outer voice coils 32 to vibrate up and down in the outer magnetic driving systems. The central cone 21 adopts a plane shape or a spherical dome at the center to emit midrange and treble sound, and the outer cones 22 of a plane shape increase and expand the bass performance of the loudspeaker, broadens the frequency bandwidth and directivity of the loudspeaker, and reduces the distortion of the loudspeaker; through the combination of the central voice coil 31 and the plurality of outer voice coils 32, and through driving the plurality of cones by the central magnetic driving system 4a and the outer magnetic driving systems 4b, the sensitivity of the loudspeaker is increased; the central cone 21 adopts a plane or spherical structure, and the outer cones adopt a flat-plate shape and inner and outer edge rings, so that the height of the cones are reduced, thus reducing the height of the product; by inputting multi-channel audio signals into the central voice coil 31 and the outer voice coils respectively, the central cone 21 and the outer cones are promoted, which can improve the sound reproduction effect of the loudspeaker; at the same time, the product has a compact structure, effectively utilizes space, and has a small overall volume that can be used as a small loudspeaker, making assembly and use more convenient.

The embodiments described above are only for illustrating the technical concepts and features of the present disclosure, are preferred embodiments, and are intended to make those skilled in the art being able to understand the present disclosure and thereby implement it, and should not be concluded to limit the protective scope of this disclosure.

What is claimed is:

1. A multi-cone small loudspeaker comprising:
a frame;
a cone assembly arranged on the frame and comprising a central cone and a plurality of outer cones, the plurality of outer cones being successively arranged in a circumferential direction of the central cone;
a central driving mechanism; and
a plurality of outer driving mechanisms arranged around a periphery of the central driving mechanism,
wherein the central cone is driven by the central driving mechanism to vibrate and sound, each of the plurality of outer cones is driven by one of the plurality of outer driving mechanisms to vibrate and sound, the central driving mechanism comprises a central voice coil connected to the central cone and a central magnetic driving system for driving the central voice coil, and each of the plurality of outer driving mechanisms comprises an outer voice coil connected to one of the

plurality of outer cones and an outer magnetic driving system for driving the outer voice coil, wherein the plurality of outer cones is interconnected to form a ring surrounding the central cone, and the central cone and the plurality of outer cones are independently arranged on the frame, wherein the frame comprises a frame bottom and an inner flange extending upwards from the frame bottom, and an outer edge of the central cone is fixedly connected to the inner flange, and wherein the frame further comprises an outer part and a plurality of middle flanges respectively extending upwards from the frame bottom, the outer part surrounds an outer periphery of the inner flange, the middle flanges are located between the inner flange and the outer part, an outer edge of each of the plurality of outer cones is fixedly connected to the outer part, an inner edge of each of the plurality of outer cones is fixedly connected to the inner flange, and two side edges of each of the plurality of outer cones are fixedly connected to two adjacent middle flanges of the plurality of middle flanges.

2. The loudspeaker according to claim 1, wherein the plurality of middle flanges radially extend along the frame bottom, and each of the plurality of outer cones is in a shape of annular sector.

3. A multi-cone small loudspeaker comprising:
a frame;
a cone assembly arranged on the frame and comprising a central cone and a plurality of outer cones, the plurality of outer cones being successively arranged in a circumferential direction of the central cone;
a central driving mechanism; and
a plurality of outer driving mechanisms arranged around a periphery of the central driving mechanism, wherein the central cone is driven by the central driving mechanism to vibrate and sound, each of the plurality of outer cones is driven by one of the plurality of outer driving mechanisms to vibrate and sound, the central driving mechanism comprises a central voice coil connected to the central cone and a central magnetic driving system for driving the central voice coil, and each of the plurality of outer driving mechanisms comprises an outer voice coil connected to one of the plurality of outer cones and an outer magnetic driving system for driving the outer voice coil, wherein the plurality of outer cones is interconnected to form a ring surrounding the central cone, and the central cone and the plurality of outer cones are independently arranged on the frame, and wherein the frame comprises a frame bottom and an inner flange, an outer part, and a plurality of middle flanges extending upwards from the frame bottom, wherein the outer part surrounds an outer periphery of the inner flange, wherein the plurality of middle flanges extends radially along the frame bottom and are located between the inner flange and the outer part, wherein an outer edge of the central cone is fixedly connected to the inner flange, and

wherein each of the plurality of outer cones is in a shape of annular sector, an outer edge of each of the plurality of outer cones is fixedly connected to the outer part, an inner edge of each of the plurality of outer cones is fixedly connected to the inner flange, and two side edges of each of the plurality of outer cones are fixedly connected to two adjacent middle flanges of the plurality of middle flanges.

4. The loudspeaker according to claim 1, wherein the central magnetic driving system and the outer magnetic driving systems are fixedly arranged on the frame bottom, and the central voice coil and the outer voice coils are located between the cone assembly and the frame bottom.

5. The loudspeaker according to claim 4, wherein the central magnetic driving system and the outer magnetic driving systems are fixedly arranged below the frame bottom, the frame bottom is opened with a central through-hole and a plurality of peripheral through-holes, a lower end of the central voice coil is inserted into a magnetic gap of the central magnetic driving system through the central through-hole, and a lower end of each of the outer voice coils is inserted into a magnetic gap of one of the outer magnetic driving systems through one of the plurality of peripheral through-holes.

6. The loudspeaker according to claim 5, wherein the frame bottom is in a shape of flat plate.

7. The loudspeaker according to claim 5, wherein each of the central magnetic driving system and the outer magnetic driving systems comprises a U-yoke having a cavity, and a magnet and a magnetic pole core arranged within the U-yoke, an upper end of the U-yoke is fixedly connected to the frame bottom, and the magnetic gap into which the central voice coil is inserted or the magnetic gap into which one of the outer voice coils is inserted is formed between the magnet and the magnetic pole core and an inner wall of the U-yoke.

8. The loudspeaker according to claim 5, wherein each of the central voice coil and the outer voice coils has a pair of leads, an end portion of each of the leads is connected with a inputting terminal capable of being electrically connected to a power amplifier, and the inputting terminal is embedded on a lower surface of the frame bottom.

9. The loudspeaker according to claim 1, wherein the inner flange and the outer part are respectively ring-shaped and concentric.

10. The loudspeaker according to claim 9, wherein the frame bottom is a circular plate as a whole, and a center of a circle of the circular plate is a center of the frame bottom.

11. The loudspeaker according to claim 1, wherein a central portion of the central cone has an upward arched spherical dome or a flat plate-shaped main body, and the plurality of outer cones have flat plate-shaped main bodies.

12. The loudspeaker according to claim 1, wherein a fixing step is formed on a lower surface of the central cone to connect to the central voice coil; and/or, a plurality of fixing steps are formed on lower surfaces of the plurality of outer cones to connect to the outer voice coils.
